UNITED STATES PATENT OFFICE.

ROBERT E. JORDAN, OF CHICAGO, ILLINOIS, ASSIGNOR TO PACKERS MACHINERY & EQUIPMENT CO., OF CHICAGO, ILLINOIS, A CORPORATION OF ILLINOIS.

TABLE CONSTRUCTION.

Application filed March 19, 1921. Serial No. 453,554.

To all whom it may concern:

Be it known that I, ROBERT E. JORDAN, a citizen of the United States, residing at Chicago, in the county of Cook and State of Illinois, have invented a certain new and useful Improvement in Table Constructors, of which the following is a full, clear, concise, and exact description, reference being had to the accompanying drawings, forming 10 a part of this specification.

This invention relates to tables and more particularly to a sanitary table construction wherein the framework of the table is made entirely of members having curved outer 15 surfaces to avoid all ledges and angular members in the construction and thus prevent the accumulation of dirt and other undesirable matter.

The general principle of the invention can 20 be applied to ordinary tables with fixed tops of any sort and to tables provided with movable tops or conveyors as well, both forms being shown in the accompanying drawings.

25 It is a purpose of the present invention to provide a table of the above mentioned character the framework of which is made up entirely of members that are substantially circular in cross section to thus avoid 30 all ledges upon which dirt or other matter may lodge.

It is a further purpose of the invention to provide a table comprising members extending vertically from top to bottom of 35 said framework upon which bracket members are mounted for securing transverse and longitudinal members thereto, said member being continuous and extending through said bracket members.

40 It is another purpose of the invention to provide a table framework comprising vertical members continuous from top to bottom thereof, connected together by means of continuous transverse members, both said 45 transverse and said vertical members having members mounted thereon having sleeve-like portions extending around said vertical and transverse members for connecting said vertical and transverse members together.

50 and for securing longitudinally extending members thereto for completing said framework. The connected transverse and vertical members form a frame or section constituting structural units any member of which 55 may be connected together by means of

longitudinally extending members to form a table of any desired length. The longitudinal, transverse and vertical members are preferably formed of tubular members circular in cross section and the connecting 60 members are preferably made in the form of castings of any desired configuration and provided with circular bores therein to receive one or more of the tubular members as desired. The tubular members preferably 65 extend through said castings or fittings and the castings or fittings are preferably held in place by means of set screws in the position that it is desired to place them to construct a table for a desired purpose. 70

It is a still further purpose of the invention to provide a table carrying a conveyor or other mechanism of a similar character with a framework of the above mentioned character provided with suitable fittings 75 mounted on any of said transverse or vertical members in any desired position thereon to properly support the mechanism mounted on said table, said fittings being passed over said tubular members so as to 80 embrace the same and being secured thereto by means of set screws or similar fastening means as described above.

It is another object of the invention to provide a conveyor on a table of the general 85 character described above that is readily cleanable and so constructed that the same can be thoroughly sterilized, said conveyor comprising pairs of side chains having individual pans arranged therebetween in 90 slightly spaced relation.

Other objects and advantages of the invention will appear as the description of the accompanying drawings showing certain forms that my invention may take proceeds. 95 However, I desire to have it distinctly understood that I do not intend to limit myself to the exact details shown or described but that I intend to include as part of my invention all such obvious changes and modifications of parts as would occur to a person skilled in this art and as would fall within the scope of the claims. 100

In the drawings:

Fig. 1 is a side elevation of my improved 105 table structure provided with a fixed top;

Fig. 2 is an end view thereof, the top being shown in dotted lines therein;

Fig. 3 is a section taken on the line 3-3 of Fig. 2; 110

Fig. 4 is a side elevation of a table constructed in accordance with my invention, said table being provided with a conveyor mechanism.

5 Fig. 5 is a section taken on line 5—5 of Fig. 4; and

Fig. 6 is a fragmentary plan view of the table shown in Fig. 4.

Referring to Figs. 1 to 3 inclusive of the drawings a table is shown comprising a framework having vertically extending posts 7 which are continuous from top to bottom of the framework. The lower ends of the posts 7 have mounted thereon the flanged sleeves or collars 8 forming feet for said posts or legs 7. Suitable transversely extending members 9 are provided which are continuous from one of said vertically extending posts or legs 7 to the other thereof and are secured thereto by means of coupling members 10 and 11. The members 10 and 11 are provided with bores or openings extending therethrough from end to end thereof and are adapted to receive the vertically extending members 7 therethrough. The members 10 are provided with laterally extending bracket or ear portions 12 having a bore 13 extending therethrough, said bore being adapted to receive the lower transversely extending member 9. The members 11 are provided with bores similar to the members 10 for receiving the vertically extending members 7 and with socket portions 14 for receiving the members 9, and with laterally projecting brackets or ears 15 each having a bore 16 extending therethrough for receiving the longitudinally extending members 17. Each of the members 8, 10 and 11 is secured to the members co-operating therewith by means of set screws 18, said screws being omitted in Figs. 1 to 3 in the drawings, except at the members 10 in Fig. 2 and the member 10 at the right of Fig. 1. The upper transverse member 9 and the upper coupling members 11 are adapted to support a stationary table top 19, the table top 19 being secured to the members 9 by means of the U-shaped strap members 50 secured to the table top 19 in any desired manner. The members 7, 9 and 17 are preferably circular in cross section as will be clear from the drawings, and the coupling members 10 and 11 and the flanged members 8 are preferably provided with curved outer surfaces so as to avoid any lodging places for dirt or other foreign matter wherever possible.

It will be noted that the members 7 and 9 and the coupling members connecting the same form a table framework section and that any one of these sections may be joined together by means of the longitudinally extending tubular members 17 form a table of any desired length.

65 It will also be seen that in constructing

tables in the manner described that the only portions thereof that would not be of standardized size would be the members 7, 9 and 11, these members varying in accordance with the size of the table by varying only 70 in one dimension, that is, the length. The same size tubing is used for all purposes so as to be adapted to be passed through the castings 8, 10 and 11 so that a single size 75 of casting for each purpose can be used for all tables.

It will also be noted that the position of the members 10 and 11 can be varied along the vertically extending members 7 if desired, the same being preferably assembled 80 with the vertical members in the following manner: The castings 8, 10 and 11 are passed over the members 7 and are bunched at the lower end thereof, the members 8 being secured in place by means of the set screws 18 85 to hold said members 8 in position at the lower extremities of the legs 7. Then the members 10 are moved upwardly along the legs 7 carrying with them the members 11 and when the members 10 have reached the 90 desired position for the same they are secured in place by means of the set screws 18 engaging the members 7. Finally the members 11 are moved into their position adjacent the upper ends of the members 7 95 and secured in place by means of the set screws. Any number of members 10 and 11 can be used, depending upon the number of transverse and longitudinal braces desired.

If desired the general principle of the 100 table construction outlined above can be applied to a table provided with a moving top or conveyor, such as is shown in Figs. 4 to 6 inclusive. In the form shown in Figs. 4 to 6 the vertically extending members 7 having 105 the flanged feet members 8 are used as previously described in connection with Figs. 1 to 3 inclusive, and these are provided with the members 10 carrying the transverse bracing members 9 as described in connection 110 with Figs. 1 to 3. The members 7 are also provided at their upper ends with the coupling members 11 shown in Figs. 1 to 3 inclusive and which are adapted to carry the longitudinally extending members 17 as described heretofore. The members 11 are used for supporting the transverse members 9' which are identical with the members 9, but which are adapted to carry the conveyor mechanism in the manner described below. 115 Mounted on the transverse members 9' are the castings 20 provided with transversely extending bores for receiving the member 9' and with vertically extending bores to receive the tubular members 21 which extend vertically and which have secured thereto at the lower ends thereof the coupling members 22, which are provided with bores extending vertically for receiving the vertically extending members 21 and with socket members 23 120

125

130

for receiving the transversely extending tubular member 24, which member 24 serves to brace and space said members 21 properly. The members 22 are provided with bracket 5 portions 25 which are adapted to receive the longitudinally extending tubular members 26 which serve as guideways for the rollers 27, which are secured to the underside of the conveyor pans 28 by means of the bracket 10 members 29. The members 9' also have mounted thereon so as to hold the same the members 30 which carry guide members 31 for the side chains 32 and the conveyor pans 28 extending between and connected to opposite 15 pairs of links 33 of said chains, as will be clear from Fig. 4. The pans 28 are slightly spaced at all times, the same being shown as being spaced when traveling in a horizontal direction, as will be seen at the 20 upper right hand side of Fig. 4. The conveyor chains 32 pass over the sprockets 34 at one end of the table framework and over the adjustable sprockets 35 at the other end of said framework, said conveyor chains being 25 driven in any desired manner. Sprockets 35 are adjustable by moving the block 36 lengthwise in the guideway 37 so as to properly adjust the tension of the conveyor chains. In a table of the character described 30 above, it is desirable to have a rigid construction due to the fact that moving parts are mounted thereon, and preferably additional coupling members 38, which are provided with bores extending therethrough 35 for receiving the members 7, are mounted on the vertically extending members 7. The members 38 are also provided with ears or 40 projections 39 providing sockets 40 which are adapted to receive the longitudinally extending bracing members 41, the same being held in place by means of the set screws 18 as previously described.

As will be evident from Fig. 4 the members 17 and 41 also serve in the type of 45 table shown to hold certain parts of the conveyor mechanism. It is of particular importance to provide a conveyor that can be readily kept in sterile condition in packing houses and similar places, especially 50 where the conveyor is used for carrying parts of the animals that have been condemned as being diseased or which are under suspicion of being diseased along with parts that have passed inspection.

It will be seen that if the conveyor is 55 not thoroughly sterilized at every revolution thereof that a conveyor section that had previously carried parts of a diseased animal might be used for carrying parts of 60 an animal that had passed inspection and thus contaminate the material that has been passed as being in a healthy condition. The material carried in a conveyor of this character usually contains quantities of 65 blood which is adapted to flow between ad-

joining sections of a conveyor having flights, such as are ordinarily used when the same pass around the sprocket wheels, and these sections being held closely together at their adjacent edges when passing 70 through a sterilizing chamber, such as the chamber 42, these edges will not be properly sterilized and the material that remains clinging thereto is quite liable to contaminate the next lot that is placed on the conveyor section. However, with the pans shown all sides thereof are exposed to the action of the sterilizing medium in the sterilizing chamber 42, and this difficulty is overcome, thus producing a more sanitary 75 device. The upper end portions of the vertical members 7 are preferably provided with the coupling members 43, which are adapted to carry the longitudinally extending guard members 44, as will be clear 80 from Figs. 4 and 5 of the drawings.

It will thus be seen that a table construction is provided that can be used both for tables with stationary tops and with tables carrying conveyors and that a very simple 90 and sanitary structure is provided which can be adapted for tables of any size and for any purpose, and that a conveyor mechanism is provided for conveyor tables that have individual pans, whereby the same can 95 be more readily sterilized.

Having thus described my invention what I claim and desire to secure by U. S. Letters Patent is:

1. A table framework of the character described comprising vertically extending members and transversely extending members connecting said vertically extending members, and means for detachably coupling said transversely extending members to 100 said vertically extending members, said vertically extending members being continuous from top to bottom of said framework, all said members having curved outer surfaces and said coupling members being 105 shiftable relative to both said vertical and transverse members.

2. A framework of the character described comprising a plurality of sections, each of said sections comprising a pair of continuous posts, a plurality of transverse members, and coupling members having socket portions for receiving said posts and said transverse members and coupling members mounted intermediate the ends of said transverse members, said last mentioned coupling members being provided with means for supporting a conveyor structure and being shiftable on said transverse members.

3. A table framework comprising continuous vertically extending members, continuous transverse members, and coupling members connecting said vertical and transverse members, said coupling members hav- 130

ing socket portions surrounding said vertical and transverse members and being provided with means to clamp said coupling members in position relative to both said vertical and transverse members, all said members having curved outer surfaces.

4. A table framework comprising continuous vertically extending members, continuous transverse members, longitudinal members, and coupling members connecting said vertical and transverse members, said coupling members having socket portions surrounding said vertical and transverse members and being provided with means to clamp said coupling members in position relative to said vertical and transverse members, certain of said coupling members being provided with socket portions to receive said longitudinal members, and being provided with means for securing said longitudinal members in position therein

5. A framework of the character described comprising a plurality of sections, each of said sections comprising a pair of continuous posts, a plurality of transverse members, said posts and members having curved outer surfaces, and coupling members having socket portions for receiving said posts and said transverse members, certain of said coupling members being disposed intermediate the ends of said posts, said posts extending through said members.

6. A framework of the character described comprising a plurality of sections, each of said sections comprising a pair of continuous posts, a plurality of transverse members, and coupling members having socket portions for receiving said posts and said transverse members and coupling members mounted intermediate the ends of said transverse members.

7. A framework of the character described comprising a plurality of sections, each of said sections comprising a pair of continuous posts, a plurality of transverse members, and coupling members having socket portions for receiving said posts and said transverse members and coupling members mounted intermediate the ends of said transverse members, said last mentioned coupling members being provided with means for supporting a conveyor structure.

8. A framework of the character described comprising a plurality of sections, each of said sections being made up of members having curved outer surfaces, said framework being provided with means for supporting a conveyor structure, said conveyor structure comprising a pair of side chains and individual pans mounted between opposite pairs of links of said chains.

9. A conveyor table having a framework comprising a plurality of sections, said sections being provided with means for supporting a conveyor structure, said conveyor structure comprising a pair of side chains and individual pans mounted between opposite pairs of links of said chains.

10. A conveyor table having a framework comprising a plurality of sections, said sections being provided with means for supporting a conveyor structure, said conveyor structure comprising a pair of side chains and individual pans mounted between opposite pairs of links of said chains, said sections having guide means for the side chains of said conveyor.

11. A conveyor table having a framework comprising a plurality of sections, said sections being provided with means for supporting a conveyor structure, said conveyor structure comprising a pair of side chains and individual pans mounted between opposite pairs of links of said chains, said pans being substantially flush with the top of said framework when in carrying position.

12. A conveyor table having a framework comprising a plurality of sections, said sections being provided with means for supporting a conveyor structure, said conveyor structure comprising a pair of side chains and individual pans mounted between opposite pairs of links of said chains, said conveyor being confined within said framework.

13. A table comprising a framework, comprising a plurality of sections, each of said sections comprising a pair of continuous posts, a plurality of transverse members, and coupling members having socket portions for receiving said posts and said transverse members and coupling members mounted intermediate the ends of said transverse members, a table top and means for securing said top to said framework.

14. A table comprising a framework, comprising a plurality of sections, each of said sections comprising a pair of continuous posts, a plurality of transverse members, and coupling members having socket portions for receiving said posts and said transverse members and coupling members mounted intermediate the ends of said transverse members, a table top and means for securing said top to said framework, said means comprising straps extending around said transverse members.

In witness whereof, I hereunto subscribe my name this 11th day of March, A. D., 1921.

ROBERT E. JORDAN.
